ATTORNEY

UNITED STATES PATENT OFFICE.

FRANK H. ROGERS, OF GOLDEN, COLORADO.

PITMAN.

SPECIFICATION forming part of Letters Patent No. 395,850, dated January 8, 1889.

Application filed May 7, 1888. Serial No. 273,043. (No model.)

To all whom it may concern:

Be it known that I, FRANK H. ROGERS, a citizen of the United States of America, residing at Golden, in the county of Jefferson 5 and State of Colorado, have invented certain new and useful Improvements in Pitman-Rods and Connections Therefor, of which the following is a specification, reference being had therein to the accompanying drawings.

10 My invention relates to an improved construction of pitmen or other connecting rods and the connections therefor, and its objects are to furnish a pitman-rod and connections of such construction that friction in the connecting parts shall be largely reduced, yet a reliable connection made—a connection having capability of automatic lubrication, in which the connecting parts are readily and easily disassociated and as readily and easily 15 reassembled, simple in construction, easily manufactured and economical in such manufacture, durable, and reliable in operation; to which ends it consists in the features and combinations more particularly hereinafter 20 described and claimed.

25 In the drawings are illustrated two forms of rods and connections embodying my invention, in which drawings—

Figure 1 is a side view of one form of rod 30 and connections; Fig. 2, a top view thereof; Fig. 3, an enlarged section of the ball or head of the ball-and-socket joint, taken on line $\alpha\alpha$, Fig. 1; Fig. 4, a side view of a rod and another form of connections, involving, however, the same principles as the first form; 35 Fig. 5, a top view thereof.

In the figures the reference-numeral 1 indicates a pitman or other moving rod to be attached to and cause to move a second rod 40 or other attached part. In Figs. 1 and 2 such second rod or part to be moved is represented by the shaft or rod 2, carrying the head 3 for forming part of a ball-and-socket joint, the other portion or socket thereof being formed 45 upon or attached to the pitman 1. Such socket is formed by the two bars, strips, or straps, 4 5, each of which is formed with a concavo-convex end, 6, the internal concavity of which is of about the same radius and 50 curve as that of the exterior of the ball 3. Of these one—in this instance strap 4—is permanently secured at the proper end of the

rod 1 by screws, bolts, or nails, while the other strap, 5, is removably attached thereto. Such strap 5 has a groove, 7, across its face near its 55 rear end, such rear end being curved or beveled underneath, as shown in Fig. 2, and it is secured at such end to the rod 1 by a loop, 8, which takes in the groove 7, and which may be fastened to the rod or merely be loose there- 60 around and around the fixed strip or strap 4. Near its front end the strap 5 has an elongated slot, 9, through which may pass the correspondingly-shaped head 11 of a bolt, 10, a pin or stop, 13, being situated to limit the 65 movement of the bolt and its head in one di- rection.

A latch-spring, 12, consisting of a strip of somewhat resilient metal, is secured at one end to the rod 1, its other end being at a small 70 angle to the general line of its body, as seen in Fig. 2, in order that while such general line of the body is at an angle to the straps 4 and 5 the angled end may be parallel to and adapt- ed to take upon or over the surface of the 75 strap 5. Projecting from such strap, and in such position that the end of the bolt-head 11 farthest from the spring-latch 12 may impinge thereagainst, is a stop-pin, 13. If now, after the bolt-head has been passed up through the 80 slot 9, it be turned to bring its right-hand end (reference being had to Fig. 1) against such pin, its motion in that direction is limited, and if then the free end of latch-spring 12 be sprung in against the side of the bolt-head 85 near its other end the bolt is prevented from turning in that direction, the spring-latch 12 and stop 13 thus holding the bolt-head and bolt securely in the position shown in Fig. 1. While the spring-latch 12 is here shown, it is 90 evident that any form of simple latch accom- plishing the same end might be used, and, if desired, be pivoted upon strap 5 itself.

In assembling the parts, strap 4 being rig- 95 idly or permanently attached to rod 1, the end of strap 5 is slipped under the loop 8, the curved or beveled end aiding both in slipping it thereunder and removing it therefrom. The head 3 is laid in the concave socket 6 of strap 4, and strap 5 is laid down thereupon, 100 the head 11 being passed through the slot 9 and then turned and locked by latch-spring 12 and stop 13. This firmly unites the parts together, they then forming a ball-and-socket

joint. If it be desired to separate the parts, the same steps are gone through with in the reverse order.

To insure thorough and automatic oiling of the bearing formed by the head 3 and concave sockets 6, the head 3 is formed, as shown in section in Fig. 3, with a hollow interior, 14, for forming a reservoir or chamber for a liquid lubricant, a suitable stopple, 15, being provided for tightly closing the mouth of the chamber. From this chamber one or more (as many as may be deemed necessary) passages, 16, lead to the exterior of the ball for conducting the lubricant to the bearing. Such passages should be so arranged that the lubricant does not flow normally therefrom, but is thrown therein and thence thereout to the bearings by the jar or concussion or shake due to operation of the parts. To this end the passages may start from above the normal level of lubricant in the chamber, as shown in full lines in Fig. 3, and thence incline downwardly, or they may start below such normal level and thence incline upwardly, with outlets above such level, as shown in dotted lines in the same figure.

When it is not desired to have the head 3 rigid upon or integral with a shaft or rod, but movably attached thereto, the same principles may be embodied in a combination similar to that shown in Figs. 4 and 5, wherein 17 is the part to be attached to and move with the pitman 1. This rod or shaft is forked at its end, 18 being the limbs or members of such fork. In this case the ball-head 3 has an aperture, 20, through it, (shown in dotted lines in Fig. 3,) in which is seated the pivotal pin 19, which is journaled in the limbs 18 of the fork of the part 17. In this modification the straps having the concavities 6, for forming the socket, are both shown as the ordinary semi-fixed straps 4 and 5, secured upon rod 1 by the bolts 21. This is merely for the purpose of illustration, as the preferable form is that shown in the other figures, preferably in that greater ease both of assembling and separating the parts is secured thereby.

While, as herein shown, the socket is attached to the pitman and the ball to the part to be moved therewith or thereby, it is evident that this relation might be reversed and the head placed on the pitman or other equivalent rod.

The construction herein described forms a very reliable and effective connection between two shafts or rods, and is well adapted for use wherever such a connection is desired or needed.

While what is herein termed the "permanently-attached strap" 4 is shown as formed separately from the rod 1 and then attached thereto by extraneous means, it is evident

that such strap 4 and the rod 1 might be formed together and be integral and homogeneous.

It will be noticed that the loop 8 and groove 7 form in effect a hinge for the rear end of the removable strap 5, and that any suitable form of hinge or pivot might be used in lieu thereof.

Having thus described my invention, what I claim is—

1. The combination of a pitman or other connecting rod, two straps thereon having concaved ends forming the socket of a joint, 75 and a second rod to be connected to the pitman-rod and carrying the head or ball of a ball-joint, the head or ball having a cylindrically-shaped lubricant-reservoir in its interior, an inclined plug or stopper therefor, and a passage or passages leading thence to the bearing to be lubricated, substantially as set forth.

2. The combination of a pitman or other connecting rod, two straps, one permanently secured thereto and one removably secured 85 thereto, both straps having concaved ends for forming a socket for a ball-and-socket joint, and a second rod or shaft carrying the head of the joint, said head having a cylindrically-shaped lubricant chamber or reservoir in its 90 interior, provided with a stopper or plug and with one or more inclined passages leading thence to the bearing to be lubricated, substantially as set forth.

3. The combination of a rod or shaft carrying the head or ball of a ball-and-socket joint, a pitman or other connecting rod, two straps, one permanently and one removably secured thereto and both formed with concaved ends for forming the socket of the joint, a loop for 100 securing the rear end of the removable strap to the rod, a bolt seated against the fixed strap and having an elongated head adapted to pass through a correspondingly-shaped slot in the removable strap, and means for 105 locking such head in holding position, substantially as set forth.

4. The combination of a pitman or other driving rod, a second rod or shaft, and a ball-and-socket joint uniting them, consisting of a 110 socket attached to one rod and a head or ball carried by the other, said head or ball having an interior cylindrically-shaped oil or lubricant chamber, a plug or stopper closing the same, and an inclined passage or passages 115 leading from the chamber to the bearing to be lubricated, substantially as set forth.

In testimony whereof I affix my signature in presence of two witnesses.

FRANK H. ROGERS.
